(57) **CLAIM**

The ornamental design for a container and lid with recess, as shown and described.

DESCRIPTION

FIG. 1 is a perspective view of the container and lid with recess;

FIG. 2 is a top view of the container and lid with recess; FIG. 3 is a side view of the container and lid with recess; and,

FIG. 4 is a bottom view of the container and lid with recess. The broken lines in the figures showing a folding utensil within the recess are for illustrative purposes only and form no part of the claimed design.
